UNITED STATES PATENT OFFICE.

JAMES F. CONNIF, OF OCONTO, WISCONSIN.

STEAM-SLED.

SPECIFICATION forming part of Letters Patent No. 400,058, dated March 26, 1889.

Application filed July 24, 1888, Serial No. 280,894. (No model.)

To all whom it may concern:

Be it known that I, JAMES F. CONNIF, of Oconto, in the county of Oconto and State of Wisconsin, have invented a new and Improved 5 Steam-Sled, of which the following is a full, clear, and exact description.

The object of the invention is to provide a new and improved sled to be propelled by steam-power and adapted to pull a train of 10 sleds.

The invention consists of certain parts and details and combinations of the same, as will be fully described hereinafter, and then pointed out in the claims.

15 Reference is to be had to the accompanying drawings, forming a part of this specification, in which similar letters of reference indicate corresponding parts in all the figures.

Figure 1 is a plan view of the power-sled. 20 Fig. 2 is a side elevation of the same. Fig. 3 is a plan view of the train of sleds, and Fig. 4 is a side elevation of the same.

The improvement consists, principally, of the power-sled A and the train of sleds composed of the sleds B B', &c., in which the front sled, B, is connected by suitable means to the rear end of the power-sled A. The latter is provided with a main frame, C, mounted on the sets of runners D and D', of which the 25 runners D' are pivotally connected at D' to the under side of the frame C, and are provided with the upwardly-extending curved ends D³, passing into the vertical slots C', formed in the frame C. Thus the runners D' 30 have a vertical swinging motion, being guided by their curved ends D³ in the slots of the main frame C.

On top of the main frame C is mounted a boiler, E, of any approved construction and 40 supplying steam to the engine F, connected in the usual manner with the main driving-shaft G, mounted to rotate in suitable bearings on the main frame C. Each of the shafts G carries a sprocket-wheel, G', over which 45 passes a sprocket-chain, G², also passing over a sprocket-wheel, G³, secured on a shaft, H, mounted transversely at the rear end of the main frame C. Each shaft H is provided with a sprocket-wheel, H', over which passes a 50 sprocket-chain, H², also passing over a sprocket-wheel, H³, secured on a shaft, I, carrying a

propeller-wheel, J. Each shaft I is mounted to rotate in suitable bearings formed on a frame, K, fulcrumed on the shaft H, so that the frame K is free to swing up and down, 55 thereby holding the propeller-wheel J in contact with the ice or snow. The periphery of each wheel J is formed by projections J', each of which has a transversely-extending sharp edge, J², adapted to cut into the snow or ice, 60 so as to firmly embed the wheel in the snow or ice, in order to propel the sled forward. As shown in Fig. 1, two wheels J are employed; but any desired number may be used and driven from the engine by any suitable means. 65

The sleds BB', &c., forming the train of sleds, connected with the power-sled A, are each provided with a reach, L, connected with the next following reach by a coupling, L', of any approved construction. On each reach L are 70 secured the transversely-extending beams N, for supporting the bed (not shown) of the sled, and a king-bolt, O, passes through the said beams N and the reaches L into the bolster P, connected with a set of runners, Q. I prefer 75 two sets of runners for each reach, as shown in Fig. 3, and I connect the front runners by chains Q' with a cross-shaft, Q², mounted on the front end of the rear set of runners. A similar cross-shaft, Q², is mounted on the front 80 set of runners and carries a forwardly-extending arm, Q³, having an upwardly-extending pin, Q⁴, passing through a slot, I², in the rear end of the reach L, and serving to hold the set of front runners in place. The chains Q', 85 connecting the front runners with the rear runners, permit the said runners to turn, as is plainly shown in the forward part of Fig. 3.

The operation is as follows: The steam supplied from the boiler to the engine F causes 90 a rotary motion of the main driving-shafts G, which, by the connections of the sprocket-wheels G' and G³ and the sprocket-chain G², impart a rotary motion to the shafts H. The latter, by their connections with the sprocket-wheels H' and H³ and the sprocket-chain H², 95 impart a rotary motion to the shafts I, so that the propeller-wheels J are rotated in the direction of the arrow a', and the steam-sled A is moved forward as the transverse edge of 100 the sharp edges J², formed in the peripheries of the wheels J, pass into the ice or snow alter-

nately, so as to propel the sled. The train of sleds B B' are connected with the rear end of the power-sled A, and are propelled forward by the latter in the manner above described.

Having thus fully described my invention, I claim as new and desire to secure by Letters Patent—

1. In a sled, the combination, with a slotted frame, of runners pivoted to the under side of the frame and having their upwardly-curved ends projecting into the slots of the frame, substantially as described.

2. In a steam-sled, the combination, with the shaft II and means for operating the same, of the frame K, pivoted on the shaft, the propeller-wheel I, journaled in the said frame, and means for operating the propeller-wheel from the said shaft, substantially as herein shown and described.

3. In a steam-sled, the combination, with a supporting-frame, the shafts G, provided with sprocket-wheels G', and means for operating the said shafts, of the shafts H, provided with the sprocket-wheels G² H', the sprocket-chain G², passing over the sprocket-wheels G' G³, the frames K, pivoted on the shafts II, the shafts I, mounted in the frames K and provided with the sprocket-wheels H³, the sprocket-chains H, passing over the sprocket-wheels H' H³, and the propeller-wheel J on the said shafts, substantially as described.

JAMES F. CONNIFF.
